(57) **CLAIM**

The ornamental design for a car double cup holder, as shown and described.

DESCRIPTION

FIG. 1 is a perspective view of the car double cup holder showing my new design;
FIG. 2 is a perspective view thereof from another angle;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a partial enlarged view of portion 9 in FIG. 1; and,
FIG. 10 is a partial enlarged view of portion 10 in FIG. 2.
In the drawings, the broken lines depict environmental subject matter only and form no part of the claimed design.

1 Claim, 10 Drawing Sheets
